UNITED STATES PATENT OFFICE.

JOSEF ULLMANN, OF VIENNA, AUSTRIA-HUNGARY.

SEALING DEVICE FOR PARCELS, &c.

No. 833,428.

Specification of Letters Patent.

Patented Oct. 16, 1906.

Application filed January 9, 1905. Serial No. 240,317.

To all whom it may concern:

Be it known that I, JOSEF ULLMANN, a subject of the Emperor of Austria-Hungary, residing at 58 Schottenfeldgasse VI, Vienna, 5 Austria-Hungary, have invented a new and useful Improvement in Sealing Devices for Parcels and the Like, of which the following is a specification.

This invention relates to improvements in 10 seals adapted for use in connection with packages bound with string, cord, or the like, and wherein the package is sealed by securing the ends of the string or cord in such manner as to effectually prevent tampering or unauthorized opening of the package without 15 effacing or destroying the seal.

To this end the invention consists in the provision of a seal composed of a strip of metal adapted to be bent upon itself around 20 the cord ends in a manner to grasp or impinge the latter and securely hold them in place, there being also provided on the foldable ends suitable interlocking parts adapted to be engaged and interlocked in a manner to 25 effect a permanent coupling of said foldable ends about the cord.

With these and other objects in view the invention consists in the construction hereinafter shown and claimed.

30 In the drawings, Figure 1 is a face view of a seal embodying the main features of my invention, the same being shown in an open position. Fig. 2 is a section on line 2-2, and Fig. 3 is a section on line 3-3, of Fig. 1. Fig. 4 35 is a face view of a modified form of my invention, and Fig. 5 is a section on line 5-5 of Fig. 4. Fig. 6 is a view of a seal as shown in Figs. 1 to 3, the same being collapsed or sealed; and Fig. 7 is a like view of the form 40 shown in Figs. 4 and 5.

First describing the form shown in Figs. 1 to 3 and 6, the same consists of a strip of metal or other suitable material, preferably rectangular, and having its outer ends 1^a and 1^b recessed, forming a marginal reinforcing-flange 1^c. A transverse rib 4 is formed near the center of the strip 1, so that when said ends are brought together, as shown in Fig. 6, to seal the cord, the bend will be regular. 45 Between the end portions 1^a and 1^b and the rib 4 are formed two cord-receiving recesses 5, adapted to register when said ends are brought together. The transverse rib 4, which insures a bend of the strip at right 50 angles to its length, also serves to bring the cord-receiving recesses into accurate regis-

ter. In each of said recesses I form cord-impinging prongs, adapted to firmly grasp the cord when the latter is sealed, this feature being realized in the forms shown by applying a punch and causing the formation of one or more sharp prongs or projections 60 3. In one end 1^a of the strip is formed a projecting flange 7, adapted to register with an aperture 6, formed in the opposite end 1^b. 65 In sealing, the ends of the cords are drawn through the holes 2, the cord entering the seal from the right being passed through the left hole, or vice versa, or they may be inserted in the recesses 5 until the ends are adjacent the prongs 3. The ends 1^a and 1^b are then brought together on a line of the rib 4, as shown in Fig. 6, until the reinforcing-flanges 1^c contact, the flange 7 registering with the aperture 6 and projecting there- 70 through. The flange 7 is spread or upset on the wall of the aperture 6, thereby firmly locking the ends together, which operation may be effected by any suitable means.

In the form shown in Figs. 4, 5, and 7 80 there is no provision for drawing the cords through holes 2, as in the first form, the cords lying transversely of the seal. Prongs 3 are disposed throughout the width of the seal to engage the cords at different points and insure firm anchorage. In this form the features of construction are otherwise similar to the form shown in Figs. 1 to 3 and 6.

What I claim is—

1. A seal comprising a strip of material 90 adapted to be folded upon itself and around a cord or the like, said strip having a transverse rib and registering recesses for receiving the cord, and cord-impinging prongs formed in the walls of said recesses, said 95 strip also having registering parts adapted to be interlocked to lock the folded ends together.

2. A seal comprising a strip of material adapted to be folded upon itself and around 100 a cord or the like, said strip having a transverse rib, and registering recesses to receive the cord, said recesses having cord-impinging prongs, and parts formed in said strip and adapted to be interlocked to lock the ends 105 together.

In testimony whereof I affix my signature in presence of two witnesses.

ULLMANN, JOSEF.
